(57) **CLAIM**

The ornamental design for a clamp with an articulating extension, as shown and described.

DESCRIPTION

FIG. 1 is a raised perspective view of a clamp with an articulating extension showing our new design.

FIG. 2 is a right side view of a clamp with an articulating extension.

FIG. 3 is a left side view of a clamp with an articulating extension.

FIG. 4 is a rear view of a clamp with an articulating extension.

FIG. 5 is a front view of a clamp with an articulating extension.

FIG. 6 is a top view of a clamp with an articulating extension.

FIG. 7 is a bottom view of a clamp with an articulating extension; and,

FIG. 8 is a perspective view of a clamp with an articulating extension.

The broken lines shown represent environmental subject matter and form no part of the claimed design.
